[57] CLAIM

The ornamental design for a multi-vial level attachment
for hand-held drills, as shown and described.

DESCRIPTION

FIG. 1 is a front, top and left side perspective view of
the multi-vial level attachment for hand-held drills
showing my new design, the rear view being plain and
unornamented.

FIG. 2 is a front, top and right side perspective view
thereof;

FIG. 3 is a left side elevational view thereof.
